Primary Examiner — Cynthia Ramirez*Assistant Examiner* — L. Martinez(74) *Attorney, Agent, or Firm* — Ralph E. Jocke; Walker & Jocke(57) **CLAIM**

The ornamental design for a bracelet, as shown and described.

DESCRIPTION

FIG. 1 is a front, top and right perspective view of a bracelet, showing our new design.

FIG. 2 is a front view thereof.

FIG. 3 is a side view thereof.

FIG. 4 is a front top right exploded perspective view thereof.

FIG. 5 is an enlarged top plan view of an attachment piece of the bracelet in FIG. 1, shown alone for convenience of illustration; and,

FIG. 6 is an enlarged view of a portion of the bracelet, taken from the marked area in FIG. 4.

1 Claim, 6 Drawing Sheets(56)
